(57) **CLAIM**

The ornamental design for a suit bag, as shown and described.

DESCRIPTION

FIG. 1 is a perspective view of a suit bag showing my new design;

FIG. 2 is another perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of portion 9 of FIG. 1;

FIG. 10 is an enlarged view of portion 10 of FIG. 2;

FIG. 11 is an enlarged view of portion 11 of FIG. 2;

FIG. 12 is an inside view thereof, shown the suit bag in a full opened position; and,

FIG. 13 is another inside view thereof, shown the suit bag in partial opened position with a suit in the suit bag.

The equally broken lines illustrate portions of the suit Bag. The dash-dot broken lines illustrate portions of that bag which are shown enlarged. None of the broken lines form part of the claimed design.
